UNITED STATES PATENT OFFICE.

ALEXANDER H. GEE, OF PILOT POINT, TEXAS.

RAIL-FASTENER.

1,283,726.

Specification of Letters Patent.

Patented Nov. 5, 1918.

Application filed March 19, 1918. Serial No. 223,360.

To all whom it may concern:

Be it known that I, ALEXANDER H. GEE, a citizen of the United States, residing at Pilot Point, in the county of Denton and 5 State of Texas, have invented a new and useful Rail-Fastener, of which the following is a specification.

This invention relates to rail fasteners and more particularly to that class in which the 10 use of the ordinary spikes is eliminated.

The object is to provide a simple device for this purpose which is capable of securely holding rails of different sizes, and which will effectually prevent their lateral 15 placement when once the means for clamping the rails have been properly tightened.

Another object is to provide a rail fastener which may be used in conjunction with the ordinary wooden tie, or with cement 20 or metal ties, and to provide means for shielding the necessary bolt holes for the reception of clamping bolts, as to exclude water or moisture therefrom, and, in the use of wooden ties, thus preventing rotting of 25 the tie; and the invention further contemplates means for preventing the accidental loosening of the clamping means through the jars and shocks incident to railroad travel.

30 A full and complete understanding of the invention may be obtained from a consideration of the following detailed description taken in connection with the accompanying drawing forming a part of this specification; it being understood that while the drawing shows a practical form of the invention, the latter is not confined to strict conformity therewith, but may be changed or modified, so long as such changes or modifications 35 40 mark no material departure from the salient features of the invention, as specifically pointed out in the appended claim.

In the drawing, in which like reference characters designate similar parts throughout the several figures:

Figure 1 is a transverse sectional view of a rail, held in position upon a tie by the improved rail fastener, the latter and the tie being shown partly in elevation and partly 50 in section, and the left hand nut being shown in loosened position and the retaining pin omitted.

Fig. 2 is a top plan view of the same.

Fig. 3 is a sectional view, taken on the line 55 3—3 of Fig. 2, and looking in the direction indicated by the arrow.

Ordinarily rails are fastened to wooden ties by driving spikes into the tie, close to the flange of the rail, as is well known, the spikes being out of alignment with each other, or staggered to prevent splitting of the said tie, but this method, though commonly employed, has three principal defects or objections. The tie is often split notwithstanding the said staggered disposition of 60 the spikes, and water soon penetrates the wood into the holes formed by the spikes when they are driven in, thus causing the tie to rot and to become useless and requiring frequent replacement, and the spikes soon 70 become loosened and displaced, thus permitting the rails to spread which oftentimes causes great disasters.

The present invention is designed to eliminate these objectionable features of rail 75 fasteners, the means for accomplishing which may be used equally well on wooden, cement or metallic ties now being used on different railroads throughout the country.

In the drawing, there is illustrated a common wooden tie 1, shown supporting an ordinary rail 2, adjacent to its end, as is customary. The flange 3 of the rail rests upon a tie-plate 4, formed of metal of sufficient thickness to withstand the strain of 80 supporting the rail and prevent the same from wearing away the wooden tie. The tie-plate 4 is somewhat less in width than the width of the tie and is considerably greater in length than the width of the rail-flange 3, so that ample space is provided for mounting, upon the terminal portions of said tie-plate, certain fastening means 85 about to be described.

Adjacent to diagonally opposite corners, 95 the tie-plate is provided with suitable apertures for the reception of vertically disposed fastening bolts 5—5, as clearly shown in Fig. 2 of the drawing, the tie being correspondingly bored, as at 6—6, to permit the 100 said bolts to traverse the same. The bolts 5—5 are provided with square heads 7—7, fitting in corresponding sockets 8—8 formed in the under side of the tie, to prevent the bolts from turning, when applying the binding nuts 9—9, at the upper threaded ends thereof.

Fastening clips 10—10 are mounted upon the exposed ends of the tie-plate 4, and are provided with suitable perforations 11—11 110 for the reception of the bolts 5—5, which thus locate the said clips in staggered rela-

tion to each other and upon opposite sides of the rail 2.

The fastening clips 10—10 are each provided with angularly bent, inclined inner portions 12—12 overhanging the flange 3 upon each side of the rail and extending to a point adjacent to the web thereof. The inner portions of the clips are bent at substantially the same inclination as the upper 10 face of the rail-flange and are adapted to be securely clamped down thereupon, when the nuts 9 are tightened, so as to prevent any lateral movement of the rail.

The perforations 11—11, formed in the 15 clips, are located adjacent to the angles of their bends, and the bolt holes in the tie-plate 4 are spaced away from the edges of the rail-flange 3 a considerable distance, as clearly shown in Fig. 1 of the drawing, so 20 that ample space is provided between the bolts 5—5, for the introduction of various sizes of rails and it will be seen that the inner portions 12—12 of the clips will effectually clamp the same, when the nuts are 25 tightened.

The nuts 9—9 have their lower corners cut away, as indicated at 13—13, so as to avoid binding against the inclined inner 30 portions of the clips and prevent the turning of the nuts to tighten the same.

In order to secure the nuts in their set positions, vertical pins 14—14 are adapted to enter through suitable apertures 15 and 16, respectively, formed in the clips and tie-plate and registering with a socket or bore 35 17 provided in the tie 1.

The socket or bore 17 is somewhat smaller in diameter than the pins 14, so that the latter, which may pass freely through the 40 registering perforations 15 and 16, formed in the clips and tie-plate, will of necessity, have to be driven into the said bore 17, when the same will be effectually held in position therein.

The pins 14 are each provided with a rectangular head 18, adapted to lie, when the pin is in position, against the adjacent face of the nut 9 and prevent the accidental turning of the same upon the threaded 45 up- per end of the bolt 5. Likewise the pin 14 is prevented from any turning movement 50

within its respective bore 17, owing to its abutting relation to the nut 9.

The opposite lower edges of the rectangular head 18 of each pin 14 are cut away or 55 beveled, as at 19, in order that an ordinary claw bar may be introduced thereunder and the pin pried from its seat in the tie. It will be noted that the clips 10—10 are held in place by the combined holding force of 60 the bolts and nuts and the pins.

From the foregoing it will be seen that an extremely simple, cheap and durable rail fastening device has been provided, which is capable of use in connection with any of 65 the kinds of ties now in use for the proper support of different sizes of rails, that the same has few parts to become worn or broken, and by reason of this fact, may be easily manipulated to apply and adjust the 70 rails in perfect alinement, when laying the same, and may be as easily released to change or replace the same.

What is claimed is:—

In combination with a railroad tie and 75 rail, a tie-plate having spaced pairs of perforations arranged diagonally opposite each other, fastening clips adapted to rest upon the tie-plate at opposite sides of the rail and having spaced pairs of perforations in 80 registering relation with the first named perforations, the inner opposed ends of the clips being bent upwardly to rest upon and engage the top surface of the rail flanges, vertical bolts traversing the inner perforations and the tie, with their threaded ends 85 up, nuts adapted to the same and having engagement with the clips, and headed pins traversing the outer perforations and adapted to be driven into smaller bores formed in 90 the tie, the said heads resting against the sides of the nuts to prevent their turning, and having their undersides beveled to be engaged by a claw bar.

In testimony that I claim the foregoing 95 as my own I have hereto affixed my signature in the presence of two witnesses.

ALEXANDER H. GEE.
